UNITED STATES PATENT OFFICE.

LUDO J. WARNER, OF CHICAGO, ILLINOIS.

FREIGHT-CAR OR THE LIKE.

1,072,887.

Specification of Letters Patent. Patented Sept. 9, 1913.

Application filed December 26, 1911. Serial No. 667,885.

To all whom it may concern:

Be it known that I, LUDO J. WARNER, a citizen of the United States, residing at Chicago, in the county of Cook and State 5 of Illinois, have invented certain new and useful Improvements in Freight-Cars or the Like, of which the following is a description.

My invention belongs to that general class 10 of cars known as freight cars, and relates particularly to a convertible refrigerator, or similar car, which may be used for transporting meats, poultry, dairy products, fruits, vegetables and the like, either one 15 kind exclusively, or mixed freights, or which may be used to transport any general or special line of merchandise or manufactures usually carried in what are known as box cars or the like. Often the cars are 20 used for carrying one kind of freight when going in one direction, and an entirely different class of freight when returning to the starting point, and when equipped with my construction, the car is applicable for any 25 class of merchandise. With my construction suitable removable decking and partitions are provided, which may be varied in their arrangement, depending upon the use of the car, or that is the freight to be carried.

30 My invention has among its objects the production of a car of the kind described that is adapted for any use, that is simple, convenient, durable, efficient and satisfactory.

35 To this end my invention consists in the novel construction, arrangement and combination of parts herein shown and described, and more particularly pointed out in the claims.

40 In the drawings wherein like reference characters indicate like or corresponding parts, Figure 1 is a vertical longitudinal sectional view of a portion of a refrigerator car equipped with my improvement. Fig. 45 2 is a vertical cross sectional view taken substantially on line 2, 2 of Fig. 1. Fig. 3 is a perspective view of a portion of a car interior equipped with my construction, all but a portion of one side of the car re- 50 moved to more clearly show my improvement, and Fig. 4 is a perspective view of one end of a rod.

Referring to the drawings, in which, to 55 illustrate my invention, I have shown a portion of a refrigerator car, consisting of the floor 1, side walls 2 and 3, and roof 4, provided with door openings 5 on each side,

and with an ice compartment or chamber 6. I do not wish, however, to be understood as limiting myself to a refrigerator car or any 60 particular construction of the car body, walls, etc., as the same may be of any suitable construction, my invention being applicable to all constructions in so far as I am aware. 65

My invention broadly consists in suitable means for forming or providing movable decks and transverse partitions on the interior of the car, which partitions may be removed and stowed away when it is not desirable to use the same. On each side of the car I secure one or more supporting parts, arranged to support suitable rods extending across or transversely the car, so that the same form an additional floor or deck and 70 partitions. For illustration, I have shown three bars on each side, a lower bar 7, an intermediate bar 8, and a top or storing bar 9, the same extending from the ends of the car to the door, or to any other intermediate 75 points. The bars 7, 8 and 9, are arranged in pairs on the sides of the car, and are provided with notches 10, 12 and 13 respectively (see Fig. 3). I also provide suitable brackets 14, 15 and 16, correspondingly arranged 80 on each side of the car at intervals from the ends to the door. To form the deck and partitions, I employ a number of preferably tubular rods 17, 18, 19, and 20, which may be supported in the notches of any pair of 85 bars 7, 8 and 9. The bars may be supported in any of the notches, depending upon the freight to be carried, and when carried in the notches 13, are out of the way, the bars 9, 9 forming substantially a rack for stowing them away. In the drawings I show several different combinations, or ways of arranging them, it being understood that 90 they may be arranged as desired. 95

To prevent the removal of the bars from 110 the car, I preferably secure each bar to the sides of the car by a flexible connecting member, as shown, chains 21 secured to the bars 17, and chains 22, 23 and 24 secured to the bars 18, 19 and 20 respectively. The 105 chains may be secured to the rods in any desired manner, as for example, referring to Fig. 4, by a link 36 connected to the rod at 37. The other ends of the chains are secured to the sides of the car by staples 25, 110 or their equivalents. In the drawings, I have shown a chain at each end of each rod, but it is, of course, understood that one chain for each rod is sufficient for the pur-

pose. The chains are made of sufficient length and are attached to the side walls so that the bars 17 may be supported on any of the supporting bars 7, 8 or 9, and the bars 18 in the brackets 16 or on the bar 9, the rods 19 in the brackets 15, or on the bar 9, and the rod 20 in the brackets 14, or on the bar 9. In this construction it is comparatively a simple matter to form horizontal or vertical partitions in the car as desired. Where dressed beef or similar freight is carried, the same may be suspended from the several rods which are carried in any of the bars, but preferably when supported on the upper bars 9. To support the rods at their centers when so loaded, and prevent them from sagging, hooks 28 may be secured to the top of the car, the same being carried from a base 27. The freight is then suspended from hooks (not shown) carried by the rods. At each side of the door additional brackets 30 and rods 31 therefor, may be provided, in which case the same may, if desired, be secured at one end by chains 32 to the side of the car by staples 33 or the equivalent. For supporting the rods, when not in use, I provide hooks 34, so that the rods may be hung out of the way. In this construction chains are employed at only one end, so that the opposite end may be swung around to one side of the car, and hung on the hooks 34.

The bars 7, 8 and 9, and any desired number of additional ones (not shown) may be arranged where desired, and the same be provided with any number of notches. There may be any number of brackets employed and any desired number of rods. It is not necessary that a rod be provided for each notch, as there may be more notches than rods, and additional rods other than those shown may be provided, permitting multiple decking, etc. The bars and rods strengthen and stiffen the car, and do not in any way decrease the carrying capacity of the car.

It may be noted that the construction herein described is very simple, and may be installed at comparatively low cost. When employed on a car, as for example on a refrigerator car, the car may be quickly converted from an open car to a car suitable for carrying dressed beef or the like, or into a double decked car, either refrigerator or as a common box or freight car for carrying any form of freight. One end of the car may be arranged as desired, that is double decked or divided, or used for one kind of products, and the opposite end of the car be left clear or free and dressed beef or other freight put therein. Where mixed freight is carried, as for example, dressed poultry, and eggs, the eggs 65 may be carried on the rods. Also with

freight, such as eggs or the like, where it is not desirable to load too much in a stack on account of the excessive weight on the lower stacks, the double decking may be positioned so that the load is distributed 70 and not all carried by the lower crates. Free ventilation or circulation of cold air throughout the car is also an additional advantage. By inserting what I have termed the vertical dividing rods, the load of freight is thoroughly braced at intervals, and cannot shift or topple over, which is particularly important where eggs make up a part of the freight. By placing the rods at the door extending from the floor 75 to the roof, as shown in Fig. 2, it is unnecessary to use other bracing at the center of the car, as for example, in the case of a load of dairy products, fruit, vegetables, or similar freight.

By using this construction of double decking and partitioning, the same may be positioned as the car is loaded, so that it is not at any time in the way, as for example, the car may be loaded at one end, then the vertical and decking rods positioned, then the double decking, if double decking is desired, and then again the vertical partitions, etc., until the car is loaded to the door. I have particularly mentioned the 90 same as applicable for refrigerator cars, which cars are often owned by private individuals, or special carrying contractors, and sent to their destination with perishable products as freight. They are usually 100 then loaded with different kinds of merchandise and returned to their starting point, or its vicinity, so that the car does not have to return empty. It is therefore of the utmost importance in having a car of 105 this kind that is not only capable of carrying perishable freight, or the products for which the car is intended, but one that is also adapted for carrying other freight, so the same may be used as an ordinary 110 freight car on its return, if necessary. With my construction the uses of the car with its double or multiple decking and partitions are unlimited.

Having thus described my invention, it is 115 obvious that various immaterial modifications may be made in the same without departing from the spirit of my invention, hence I do not wish to be understood as limiting myself to the exact form, construction, arrangement or combination of parts herein shown and described, or uses mentioned.

What I claim as new and desire to secure by Letters Patent is:—

1. In a car, a plurality of vertically spaced longitudinally extending bars on each side of the car, the bars on each side having a plurality of engaging parts in alinement with similar parts on the co-operating bar 130

at the opposite side of the car, a plurality of transversely extending rods adapted to be supported at the ends by said engaging parts and to be shifted from one pair of bars to another, an auxiliary connection between the rods and the car, said last mentioned connection being movable to permit of said adjustment of the rods, and bracket supports on the sides of the car for the ends of the rods arranged intermediate said longitudinally extending bars.

2. In a car, the combination of a plurality of rods extending horizontally from one wall of the car to an opposite wall thereof, a supporting member for one end of the rods having a connection with the rods adjacent one end and with the adjacent wall of the car, relative fixed supports on opposite walls of the car for opposite ends of said rods, said first mentioned supporting member being movable whereby to permit the rods to be moved into and out of engagement with the relatively fixed supports.

3. In a car, the combination of a plurality of tubular rods arranged transversely the car, movable means for attaching said rods to one side of the car, and means for supporting the ends of said rods in adjusted positions.

30 4. In a car, a plurality of vertically spaced longitudinally extending bars on each side of the car, the bars on each side having a plurality of engaging parts in alinement with similar parts on the coöperating bar at the opposite side of the car, a plurality of transversely extending rods adapted to be supported at the ends by said engaging parts and to be shifted from one pair of bars to another, a relatively fixed flexible connection between the rods and the car, and bracket supports on the sides of the car for the ends of the rods arranged intermediate said longitudinally extending bars.

45 5. In a car, the combination of a bar arranged along each side of the car and having separated engaging parts, a plurality of rods removably supported by said engaging parts, and a flexible member connected to the bar and to the side of the car for preventing the removal of the rods from the car.

50 6. In a car, the combination of a plurality of similarly arranged bars on each side of the car extending from the ends thereof, said bars having a plurality of rod engaging notches, a plurality of rods extending transversely the car from one of the bars on one side to the corresponding bar on the opposite side, and removably supported thereby, and means for attaching one end of each rod to the side of the car.

60 7. The combination in a car of a plurality of pairs of bars arranged on the interior of

the car, one pair of bars secured to one side of the car proximate the top thereof, and the other pair of the bars similarly arranged on the opposite side of the car, the other pairs of bars arranged at intermediate points between the floor and the top bar, said bars having spaced recesses forming rod engaging parts, a plurality of rods extending transversely the car and arranged to co-operate with any of said pairs of bars and be supported thereby, and flexible means for securing one end of each of said rods to one side of the car.

8. The combination in a car of a plurality of bars arranged on each side of the interior of the car, the bars on one side arranged opposite the bars on the other side, each of said bars provided with a plurality of notches therein, a plurality of rods arranged within the car and extending from side to side thereof, said rods supported by the corresponding bars at the sides of the car, a plurality of brackets arranged vertically at intervals along each side of the car, a rod for each pair of brackets, and means for securing all of said rods to the car.

9. In a car, a plurality of vertically spaced longitudinally extending bars on each side of the car, the bars on each side having a plurality of engaging parts in alinement with similar parts on the coöperating bar at the opposite side of the car, a plurality of transversely extending rods adapted to be supported at the ends by said engaging parts and to be shifted from one pair of bars to another, and an auxiliary connection between the rods and the car, said last mentioned connection being movable to permit of said adjustment of the rods.

10. In a car, a plurality of vertically spaced longitudinally extending bars on each side of the car, the bars on each side having a plurality of engaging parts in alinement with similar parts on the coöperating bar at the opposite side of the car, a plurality of transversely extending rods adapted to be supported at the ends by said engaging parts and to be shifted from one pair of bars to another and a relatively fixed flexible connection between the rods and the car.

11. In a car, the combination of a plurality of rods arranged transversely of the car, means for supporting said rods at their ends, and retaining means connected at one point to a relatively fixed support and at another point to said rod.

In testimony whereof, I have hereunto signed my name in the presence of two subscribing witnesses.

LUDO J. WARNER.
